UNITED STATES PATENT OFFICE.

ARTHUR SPENCE, OF CLEVELAND, OHIO.

DESIGN FOR A COAL-BIN.

57,869.

Specification for Design.

Patented May 10, 1921.

Application filed December 30, 1916. Serial No. 139,982. Term of patent 14 years.

To all whom it may concern:

Be it known that I, ARTHUR SPENCE, a citizen of the United States, residing at Cleveland, in the county of Cuyahoga and State of Ohio, have invented a new, original, and ornamental Design for Coal-Bins, of which the following is a specification, reference being had to the accompanying drawing, forming part thereof.

The figure is a perspective view of a coal bin, showing my new design.

I claim:

The ornamental design for a coal bin, as shown.

ARTHUR SPENCE.
